COMBINATION REFRIGERATOR AND FOOD FREEZER

William A. Allen, Syracuse, N. Y., assignor to Carrier Corporation, Syracuse, N. Y., a corporation of Delaware

Application January 3, 1955, Serial No. 33,819

Term of patent 3½ years

(Cl. D67—3)

The figure is a perspective view of a combination refrigerator and food freezer embodying my new design with the top door in open position. The front of said door not shown is substantially plain.

The dominant features of my design reside in the portions shown in full lines.

I claim:

The ornamental design for a combination refrigerator and food freezer, as shown and described.
